UNITED STATES PATENT OFFICE.

ANSEL STEVENS, OF WESTBROOK, MAINE, ASSIGNOR TO THE McCASKEY REGISTER COMPANY, OF ALLIANCE, OHIO, A CORPORATION OF OHIO.

CREDIT-ACCOUNTING APPLIANCE.

No. 867,617.

Specification of Letters Patent.

Patented Oct. 8, 1907.

Application filed December 29, 1906. Serial No. 349,962.

To all whom it may concern:

Be it known that I, ANSEL STEVENS, a citizen of the United States, residing at Westbrook, in the county of Cumberland and State of Maine, have invented certain new and useful Improvements in Credit-Accounting Appliances; and I do declare the following to be a full, clear, and exact description of the invention, reference being had to the accompanying drawings, and to the letters and figures of reference marked thereon, which form a part of this specification.

This invention relates to account cabinets or registers that are used in a credit accounting system for holding duplicate bill slips in systematic order indexed for ready reference, the invention having reference more particularly to the hinged bill holding leaves or frames and the support therefor.

The object of the invention primarily is to provide a simple and inexpensive credit register or set of bill holding leaves which may be adapted to be used without requiring a case, desk or elaborate cabinet therefor, which leaves may be readily handled as a group to be placed in a fire proof safe for security of the accounts, all to the end that appliances of the above-mentioned character may be produced at a relatively small expense for the use of merchants of limited means or those having small lists of credit customers, not warranting the purchase of more elaborate credit account cabinets now in general use.

With the above-mentioned and minor objects in view, the invention comprises a stand adapted to be placed upon a counter or a shelf, and a plurality of bill holding leaves or frames pivoted to a leaf base which is adapted to be held removably on the stand and to support the leaves either in nearly vertical or in approximately horizontal positions independently of other supports. And the invention consists further in the novel parts and in the combinations and arrangements of parts as hereinafter particularly described and claimed.

Referring to the drawings, Figure 1 is a perspective view of the improved credit register; Fig. 2, a transverse sectional view taken near the right-hand side of the register leaves with one of the leaves in its lower-most or reclining position; Fig. 3, a perspective view of the base for the bill holding leaves; Fig. 4, a top plan view of the stand; Fig. 5, an end elevation of the stand; Fig. 6, a fragmentary end elevation of the set of bill holding leaves; Fig. 7, a top plan of one of the leaves; and, Fig. 8, a side view of either one of the leaves.

Similar reference characters in the different figures of the drawings designate corresponding elements or features of construction.

The stand for the register comprises two foot pieces

a and *a'* to which a rail *b* is attached at its ends spacing 55 the foot pieces apart the desired distance, and the foot piece *a* has screw holes *c* and *d* in its end parts, the foot piece *a'* having similar holes *c'* and *d'* so that in case it is desired to place the stand upon a shelf or near the edge of a counter, the stand may be secured 60 in order to prevent it from tilting over by the overhanging weight of the leaves when drawn forward. The stand comprises also a pair of upright end pieces *e* and *e'* that are suitably attached to the foot pieces, and two arms *f* and *f'*, one arm being connected at one 65 of its ends by a pivot *g*, and the other arm connected at one of its ends by a pivot *g'* to the rail *b*, the pivots being near the foot pieces, and the arms may either fold under the rail *b* or be drawn out along side of the foot pieces to serve to prevent the stand from tilting 70 forward in case that it is not secured otherwise, these arms adapting the stand to be placed anywhere temporarily or removably. The forward end of the foot piece *a* is provided with a lip *h*, and the forward end 75 of the foot piece *a'* with a lip *h'*. The upright end pieces *e* and *e'* are triangular in elevation, arranged with one angle of each inclined so as to face forwardly, and in the rear of the upper parts thereof are notches *i* and *i'*.

The leaf base *j* for connecting together and directly 80 supporting the leaves may be composed of either wood or metal and is adapted to lie as a board or plate upon the end pieces *e* and *e'*, in slanting position with the lower edge *j'* under the lips *h* and *h'*, and an upper rear part of the base is provided with loops *k* and *k'* 85 that may be drawn into the notches *i* and *i'* to prevent the base from tilting forward.

The base is provided with a suitable number of pivots as *l* and *l'*, projecting from its ends to which the bill holding leaves are pivoted.

The bill holding leaves each comprise a frame *m* or *m'*, and a plate *n* or *n'*, each frame being preferably composed of strips secured suitably to opposite sides of the plate, the rear plate *n* being provided with a stiffening strip *o*, and the forward leaf plate *n'* with a stiffening strip *o'*. The side bars of each leaf frame are longer than and project beyond an edge of the leaf plate, and the projecting ends of the frame are provided with pivot holes *p* by which the frame is connected to the pivots *l* or *l'*. The pivot holes are arranged near the forward sides of the leaves so that when the leaves are placed vertically they will be inclined to lean rearwardly, the lower edge of the plate *n*, or a strip *o* thereof finding a bearing against the base *j*, whereby the leaf is held upright leaning slightly rearward, the rear leaf supporting the other leaves when upright, although the lower edge of the plate of each leaf also bears against the forward face of the base *j*, thus relieving

ing the rear leaf from undue strains. When the forward leaf is drawn forward as in Fig. 2, the plate n' or its stiffening strip o' , will bear against the lower forward part j' of the base, thus supporting the leaf in approximately horizontal position, and the other leaves may be drawn forward and be supported horizontally partly by the forward leaf and also by reason of the plate of each leaf engaging the front face of the base, this feature being of particular advantage when the stand may be placed near the forward edge of a shelf.

Each leaf is provided with a suitable number of spacing strips q and r , and also with bill clamps or spring clips s , formed of wire bent in U-shape with the ends thereof turned to form eyes and secured by rivets t and t' to the plate n or n' of the leaf.

It will be understood that in the credit accounting system suitable bill slips are employed and made out in duplicate, one of which is to be placed on a bill holding leaf and held by a clamp s , the leaves and the clamps 20 of course being indexed, and the operations of the system being well known, requires no further explanations.

In practical use of the invention, the set of bill holding leaves, which may comprise any suitable number, 25 may be lifted with the base thereof and placed instantly upon the stand and then will be ready for use, and when desired to remove the leaves, as in case of a fire or at other times, for security, the base j may be moved slightly upward so as to release the loops k and k' from 30 the notches i and i' , when the base and the leaves may be lifted from the stand and carried away, the advantages of which will be fully understood and appreciated.

Having thus described the invention, what is claimed as new is—

35 1. Credit - accounting appliances including a portable leaf-base, means for supporting the leaf-base fixedly in a normal operative position, and a plurality of bill-holding leaves pivoted on the leaf-base, the rearmost leaf normally supported in leaning position by contact with the base in 40 proximity to the axis of the pivot of the leaf.

2. Credit - accounting appliances including a portable stand provided with means for supporting itself normally in upright position, a leaf base mounted removably on the stand, and a plurality of bill-holding leaves pivoted on the base and leaning when in upright positions against the 45 base in proximity to the planes of the axes of the pivots thereof.

3. Credit - accounting appliances including a portable stand, a leaf base mounted removably on the top of the stand, and a plurality of bill-holding leaves pivoted on the base and leaning when in upright positions against the 50 base in proximity to the planes of the axes of the pivots thereof.

4. Credit - accounting appliances including a base provided with pivots, a plurality of bill-holding leaves each 55 comprising a plate and a frame having parts extending beyond the plate, said parts being mounted on the pivots, and the plates of the leaves engaging the base and being stopped thereby at predetermined angles thereto, the plates swinging clear of the base at other relative angles thereto. 60

5. Credit - accounting appliances including a stand provided with folding arms for its support, a base mounted removably on the stand, a plurality of bill-holding leaves pivoted on the base and leaning when in upright positions against the base, means for locking the base on the stand, 65 and means on the leaves for holding bill-slips.

6. Credit - accounting appliances including a portable stand comprising two foot pieces and a rail and also upright end pieces, the foot pieces extending beyond the end pieces and having lips on their ends, a leaf base mounted 70 removably upon the end pieces and the foot pieces and engaging the lips of the latter, and bill-holding leaves pivoted on the base.

7. Credit - accounting appliances including a portable stand comprising two foot pieces having upright end pieces 75 mounted thereon and a rail secured to the foot pieces, the foot pieces extending beyond the end pieces, the end pieces having notches in the higher parts thereof, a leaf base mounted removably upon the end parts and the projecting portions of the foot pieces and having loops held in the 80 notches of the end pieces, and bill-holding leaves pivoted on the base.

In testimony whereof, I affix my signature in presence of two witnesses, on the 17th day of December, 1906.

ANSEL STEVENS.
